W. LANDES

PROCESS FOR OBTAINING A LIGHT HYDROCARBON

Filed May 19, 1924

Patented Apr. 27, 1926.

UNITED STATES PATENT OFFICE.

WILLIAM LANDES, OF LONG BEACH, CALIFORNIA.

PROCESS FOR OBTAINING A LIGHT HYDROCARBON.

Application filed May 19, 1924. Serial No. 714,345.

To all whom it may concern:

Be it known that I, WILLIAM LANDES, a citizen of the United States, residing at Long Beach, in the county of Los Angeles and State of California, have invented certain new and useful Improvements in a Process for Obtaining a Light Hydrocarbon, of which the following is a specification, reference being had therein to the accompanying drawing.

The present invention has for its object the provision of a novel and practical process for obtaining a light hydrocarbon, such as gasoline, from petroleum or crude oil.

Another object is to utilize, in the process, casing head gas, or other suitable hydrocarbon gas, to mix and combine with the vapor of the petroleum or oil, so as to obtain the light hydrocarbon liquid in an effective and desirable manner.

The apparatus for carrying out the process, is shown in the accompanying drawing, wherein—

Figure 1 is a longitudinal vertical section of the retort and vapor chamber, and

Fig. 2 is a cross section on the line 2—2 of Fig. 1.

The chamber 7 is of suitable size, according to the capacity desired, and has a vapor dome 8 at the top thereof near the rear end of the chamber, from which the vapor discharge pipe 9 extends for carrying off the vapor from the chamber to the usual condenser (not shown). A drain pipe 10 is connected to the bottom of the chamber for drawing off the residue, and said pipe has a valve 11 which is controlled manually or automatically for the discharge of the residue from the chamber so as to maintain the

residue in the chamber at a predetermined level. In carrying out the invention, the residue in the chamber is of shallow depth, as shown in the drawing, thereby leaving a large vapor space above the liquid. The

liquid or residue in the chamber occupies about one-eighth of the chamber, leaving about seven-eighths to be occupied by the incoming vapors, so that such vapors have plenty of space for expansion and condensation.

The front end of the chamber carries atomizing nozzles 13 for the discharge of petroleum or crude oil and steam under pressure into the chamber, and said atomizing nozzles may be of any suitable kind. The oil and steam supply pipes 14 and 15 are

connected to said nozzles and have controlling valves 16.

Below the nozzles 13 there are provided the second set of nozzles 17, which project through the front end of the chamber, for the discharge of natural or casing head gas into the chamber. The gas and steam supply pipes 18 and 19 are connected to the nozzles 17, and have control valves 20, whereby the gas can be discharged into the chamber with or without steam mixed therewith.

In carrying out the process, the steam, oil and gas are discharged from the nozzles or atomizers into the chamber, the fluids being supplied to the nozzles at a pressure of 125 pounds, more or less depending on conditions. The oil and gas being discharged violently into the chamber will be subjected to mechanical energy and agitation, while the steam in being discharged into the chamber will have the opportunity for expanding and creating a cooling effect. The delivery of the vapors into the chamber is controlled whereby the vapors are delivered into the chamber at such a rate that the vapors can expand within the chamber, without the pressure accumulating, the pressure in the chamber being at or near atmospheric pressure. The residue at the bottom of the chamber is maintained at a uniform depth, and such residue is kept heated to a temperature of about 300 degrees F., a thermometer and gage 12 being provided for that purpose. The temperature of the vapors in the chamber is lower than that of the residue, being about a temperature of exhaust steam, or about 220-225 degrees F. The residue may be heated by any well-known means, such as a fire below the chamber.

The mechanical agitation of the oil resulting from the violent discharge of the oil into the chamber under pressure with the steam will result in the breaking up or cracking of the oil, thereby upsetting the molecular arrangement, and giving the strained molecules of the gas the opportunity to mix and combine with the oil molecules, to build up a physical combination which is stable the same as straight run gasoline. The oil and gas are not only discharged simultaneously into the chamber to be agitated and mixed, but the heavier fluid is delivered above the lighter fluid, whereby the gravitation of the particles of oil downward through the gas will facilitate the co-

mingling and contact of the oil and gas molecules while subjected to physical energy and agitation.

The presence of the steam causes a mild moist comparatively low temperature in the chamber, instead of using a dry heat, and there is sufficient cooling effect to create a condition so that the casing head or other gas remains assembled with the heavier hydrocarbon vapor until they reach condensation after discharging through the dome 8 and pipe 9. By the mechanical and physical energy, resulting from the atomizing action, more of the heavy hydrocarbon matter is broken up at a low temperature than is possible with dry heat and higher temperatures. The cooling effect caused by full expansion of the vapors also results in the gas, which is fed into and fused with the heavier hydrocarbon, to remain assembled therewith until the discharged vapor is condensed in the usual manner.

The unvaporized portion of the petroleum or oil drops to the bottom of the chamber, and collects as residue, and such residue is drawn off from the chamber as required to maintain the uniform depth of the residue in the chamber. Such residue is kept at a temperature somewhat above the vapor temperature, and any vapor rising from the residue will mix with the other vapors. The temperature of the residue may vary, and in some cases may be as high as 400 degrees F., depending on the depth of the residue in the chamber, the density of the residue, and other conditions.

By such process there can be obtained from the oil and gas a comparatively high proportion of light hydrocarbons, such as gasoline, it being apparent that the oil is

not only broken up to separate the lighter hydrocarbon elements therefrom, but the gas also combines with and neutralizes or dilutes some of the heavier carbon matter, so that a greater percentage of the oil or petroleum is available for the light hydrocarbon products.

Having thus described the invention, what is claimed as new is:—

1. The process of obtaining a light hydrocarbon consisting in atomizing oil with steam into a chamber, and simultaneously atomizing hydrocarbon gas with steam into the chamber independently of and below the oil so that the gas intercepts particles of oil 55 that drop from above.

2. The process of obtaining a light hydrocarbon consisting in separately atomizing both oil and hydrocarbon gas into a chamber with steam in a manner that the oil and gas will first mix when discharged into said chamber, and maintaining a shallow depth of residue at the bottom of the chamber at a higher temperature than the vapors above said residue.

3. The process of obtaining a light hydrocarbon consisting in separately atomizing both oil and hydrocarbon gas into a chamber with steam in a manner that the oil and gas will first mix when discharged into 70 said chamber, with the gas discharging into the chamber below the oil for the gravitation of particles of oil through the gas, and maintaining a shallow depth of residue at the bottom of the chamber at a higher temperature than the vapors above said residue.

In testimony whereof I hereunto affix my signature.

WILLIAM LANDES.
